Inventor.

UNITED STATES PATENT OFFICE.

GEORGE R. FLOYD, OF CINCINNATI, OHIO.

AUTOMATIC LINE-CATCH FOR TROLLEY-WIRES.

SPECIFICATION forming part of Letters Patent No. 707,222, dated August 19, 1902.

Application filed December 31, 1901. Serial No. 87,890. (No model.)

To all whom it may concern:

Be it known that I, GEORGE R. FLOYD, a citizen of the United States, residing at Cincinnati, in the county of Hamilton and State 5 of Ohio, have invented new and useful Improvements in Automatic Line-Catches for Trolley-Wires, of which the following is a specification.

My invention has relation to electric rail- 10 ways operated by current from an overhead trolley-wire through a trolley-arm upon the moving cars; and it consists of a safety attachment, which may be termed an "automatic line-catcher," operating to hold up the loose 15 ends of a trolley-wire when broken by use, so as to prevent said loose ends from dangling to or near to the ground, thus preventing injury to passers-by upon the street or trackway below. It is a matter of common 20 experience and observation that such accidental breaks take place in the great majority of cases adjacent to the "supporting-ears" by which the trolley-wire is upheld upon a span-wire or gallows-arm of a post, so that in 25 most cases the present device will be used most frequently at such supporting points or at points where a sleeve is employed to reunite the severed end of a trolley-wire. It may be used, however, wherever the conditions 30 of use or of the wire render it likely that a break may occur.

To the end indicated the invention consists in a supplemental wire or rod spanning the weak point and connected to small supplemental ears attached to the trolley-wire at 35 opposite ends of the supporting wire or rod.

My invention is illustrated in the accompanying drawings, in which—

Figure 1 is an elevation of my device complete shown in connection with the ordinary suspending-ear used with span-wires; Fig. 2, a similar elevation showing the trolley-wire broken and its severed end upheld by my device. Fig. 3 is an elevation of the device 45 as applied where a sleeve connects ends of a trolley-wire previously broken.

Referring now to the drawings, A designates a suspending-ear of common form, with insulating-cap a hung upon a span-wire B, 50 stretched, for example, between opposite posts (not shown) in the usual manner and constituting a support for the trolley-wire w .

The upward pressure of the trolley-wheel of a car produces a constant upward bending of the wire w , which is arrested by the rigidity 55 of the ear A, and in consequence the wire w is frequently broken by the constant tension of the wire and repeated molecular stresses adjacent to the ends of the ear A. The severed end when such break occurs dangles from the 60 next ear downward to the roadway below and often causes death of persons, horses, &c., by contact or by sparking contact with the earth frightens persons or horses, producing incidental damage of a serious nature. To prevent the severed end from thus falling, I attach small ears c to the trolley-wire w at 65 points beyond the zone of damage and connect them by a wire or rod d . Ordinarily I prefer to use a wire, and for convenience 70 fasten the same to the insulating-cap a , by which it is retained in a convenient position out of the way and by which also the sudden side stress brought upon the span-wire B is in a measure relieved by making the severed part of the wire w still carry the load 75 of tension. I prefer to secure the wire d to the ears c by short eyebolts c' , which are allowed a little longitudinal play to accommodate the swaying of the trolley-wire in ordinary use, so that no strain whatever is suffered by the automatic catch device except in 80 case of breakage of the trolley-wire w .

The method of operation is obvious and is illustrated in Fig. 2. The wire w being 85 broken between the ears c is upheld by the wire d , connecting said ears until proper repairs can be made. The application of the device to the other parts of the trolley-wire is practically the same. In Fig. 3 is shown a 90 case where a previous break is mended by a sleeve e . Here are presented substantially the same conditions as in case of the ear A, where by reason of the rigidity of the sleeve e a break is liable to occur at either end. In 95 such case there being no element by which the wire d may be independently supported I employ a stiff wire or rod capable of sustaining itself, the device and its action being the same as already described.

I claim and desire to secure by Letters Patent of the United States—

1. In combination with a trolley-wire an automatic safety device consisting of a supple-

mental wire or rod, connected to the trolley-wire at opposite sides of and beyond a point of probable breakage, by suitable holding-ears, said wire having a limited longitudinal movement in said ears.

2. In combination with a trolley-wire having holding-ears fixed to it at opposite sides of and beyond a point of probable breakage, an automatic safety device consisting of a supplemental wire or rod connected to said ears, the ends of said wire or rod having a limited longitudinal movement in said ears.

3. In combination with a trolley-wire and

holding-ears thereon at opposite sides of and beyond a point of probable breakage, an automatic safety device consisting of a supplemental wire or rod leading from a fixed point and connected to the ears and having a limited longitudinal movement therein.

In testimony whereof I have hereunto set my hand in presence of two subscribing witnesses.

GEORGE R. FLOYD.
